UNITED STATES PATENT OFFICE.

CHARLES H. PARTINGTON, OF CINCINNATI, OHIO, ASSIGNOR TO THE CINCINNATI FROG & SWITCH COMPANY, OF CINCINNATI, OHIO, A CORPORATION OF OHIO.

CONNECTING-ROD FOR SWITCH-THROWS.

1,383,334.

Specification of Letters Patent.

Patented July 5, 1921.

Application filed May 6, 1921. Serial No. 467,427.

To all whom it may concern:

Be it known that I, CHARLES H. PARTINGTON, citizen of the United States, residing at Cincinnati, in the county of Hamilton and 5 State of Ohio, have invented certain new and useful Improvements in Connecting-Rods for Switch-Throws, of which the following is a specification.

This invention relates to an improved 10 spring connecting rod for switch throws and has as one of its principal objects to provide a rod which will freely permit movement of the points of a switch independently of the throw therefor but wherein the throw may 15 be operated for setting the switch in either open or closed position.

The invention has as a further object to provide a connecting rod wherein, without regard as to whether the switch is set in open 20 or closed position, the switch points will, when shifted independently of the switch throw, be yieldably returned to the original set position of the switch.

And the invention has as a still further object to provide a connecting rod which will 25 be structurally feasible and which in actual practice will operate with entire efficiency and dependability.

Other and incidental objects will appear 30 hereinafter.

In the drawings:

Figure 1 is a fragmentary plan view showing my improved connecting rod in connection with a switch and switch throw of conventional design.

Fig. 2 is an enlarged sectional view showing the rod when the switch is closed,

Fig. 3 is a view similar to Fig. 2 at right angles thereto, showing the rod when the 40 switch points are moved away from closed position independently of the switch throw,

Fig. 4 is a view similar to Fig. 3, showing the rod when the switch is open,

Fig. 5 is a like view showing the rod when 45 the switch points are moved away from open position independently of the switch throw,

Fig. 6 is a transverse sectional view on the line 6—6 of Fig. 4, looking in the direction of the arrows,

Fig. 7 is a transverse sectional view on the line 7—7 of Fig. 3, looking in the direction of the arrows, and

Fig. 8 is an end elevation showing the closure plug of the rod.

55 Referring now more particularly to the

drawings, I have, for convenience, shown my improved connecting rod in connection with a switch and switch throw of conventional design. In Fig. 1, main track rails are indicated at 10 and side track rails at 11. 60 At 12 are shown coacting switch points and connecting these switch points to move in unison is a tie bar 13. The switch is shown closed, the switch point at the right of the figure being moved away from the adjacent 65 main track rail. In the open position of the switch, the switch points are, of course, shifted to a position reverse to that illustrated. The base plate of the switch throw is indicated at 14, this plate being spiked to 70 one of the track ties and journaled upon the plate is a customary switch throw lever 15. Coming now more particularly to the subject of the present invention, it will be seen that I employ coacting telescopic rod sections 16 and 17, the section 16 being solid and the section 17 being hollow. At its forward end the section 16 is provided with a yoke 18 bolted to the adjacent end of the tie bar 13 while at the forward end portion of 80 the section 17 are provided spaced aligned bearings 19 and 20 slidably receiving the section 16 therethrough. In the rear of the bearing 20, the section 17 is, as shown in detail in Fig. 6, formed with a squared portion 21 merging at a point substantially midway between the ends of the section into a cylindrical rear end portion 22. Threaded upon the section 16 within the portion 21 of the section 17 is a nut 23 disposed to coat 85 90 with the bearing 20 for preventing separation of the rod sections and, as will be observed, the walls of the portion 21 of the section 17 will limit the nut against rotation. Consequently, the section 16 of the rod may 95 be rotated with respect to the section 17 for threading the former section through the nut and varying the effective length of the rod.

Formed in the cylindrical portion 22 of the rod section 17 are registering slots 24 100 and slidable within said section is a hollow plunger 25 open at its forward end to receive the rear end of the rod section 16 and provided at its rear end with a head 26. The plunger is, as shown in Fig. 6, substantially rectangular in cross section to freely fit within the portion 21 of the section 17 of the rod but is, however, provided with rounded corners to also freely fit, as shown in Fig. 7, within the cylindrical portion 22 110

of the rod section while the head 26 overhangs the body of the plunger and more nearly approaches the wall of the portion 22 for centering the inner end of the plunger 5 with respect to said wall. Formed in the plunger at opposite sides thereof are registering slots 27 alining with the slots 24 of the rod section 17 and extending freely through all of said slots is a pin 28 which, 10 as shown in Fig. 7, is fixed to the switch throw lever 15. Preferably, a washer 29 is arranged between said lever and the rod section 17 while upon the outer end portion of the pin is mounted a second washer 30, a cotter pin being arranged to coact between this washer and the pin for securing the rod upon the pin. At its outer end, the rod section 17 is, as particularly shown in Fig. 8, formed with oppositely disposed lugs 31 directed inwardly toward the axis of said section and arranged to coact with said lugs is 15 a removable closure plug 32. This plug is provided with an annular radial base flange 33 freely fitting within the outer end portion 20 of the rod section 17 and formed in said flange are diametric notches 34 adapted to freely receive the lugs 31. Rising from the flange are pairs of reinforcing ribs 35, each pair of ribs receiving one of the lugs there- 25 between respectively. Accordingly, the ribs will coact with the lugs for locking the plug against rotation and bearing between said plug and the head 26 of the plunger 25 is a coil spring 36 housed within said rod sec- 30 tion. As will be perceived, the plug may be depressed into the rod section against the tension of said spring until the ribs 35 clear the lugs 31 when the plug may then be rotated to bring the notches 34 into register 35 with said lugs. In this position of the plug, said plug may, of course, be removed to permit removal of the spring 36 and plunger 25. In this connection, it is to be observed that the rod section 17 is provided with an en- 40 larged rear terminal 37 to accommodate the plug, said terminal carrying the lugs 31. The lugs are accordingly spaced away from the axis of the rod section so as to lie substantially flush at their inner ends with the inner face of the wall of the portion 22 of the section whereby the head 26 of the plunger may clear said lugs. I accordingly provide 45 a construction wherein the rod may be readily assembled or disassembled.

50 As will now be readily understood in view of the preceding description, the spring 36 will normally maintain the parts in the position shown in Fig. 2, so that the switch throw lever 15 may be swung to shift the switch points 12 for opening or closing the switch. However, when the switch is closed, as shown in Fig. 1, it will be seen that the switch points may move for drawing the rod section 17 forwardly over the pin 28, as 55 shown in Fig. 3, and compressing the spring

36, the plunger slidably supporting the rod for bodily longitudinal movement. Then, when the switch points are released, the spring will act to immediately return the switch points to their original position. Fig. 4 shows the position of the rod when the switch is open. Movement of the switch points toward closed position will then, as shown in Fig. 5, serve to telescope the rod section 16 into the rod section 17 and shift the plunger 25 rearwardly in the latter rod section, compressing the spring 36. Accordingly, when the switch points are released, the spring will serve to immediately return the switch points to their original position. 70 Thus, as will be seen, when the switch is closed, rolling stock may move, in the direction of the arrow in Fig. 1, from the rails 11 onto the rails 10, shifting the switch points, while when the switch is open, rolling stock may move from the rails 10 onto the rails 11, the switch points being similarly shifted. Furthermore, in each instance, the switch points will be yieldably returned to the original position in which the switch is 75 set.

Having thus described the invention, what is claimed as new is:

1. A switch throw rod including slidably connected rod sections, means for slidably supporting the rod for bodily longitudinal movement, and yieldable means between one of the sections and the first means for resisting longitudinal movement of the rod as well as sliding movement of one section 95 relative to the other common to both movements.

2. A switch throw rod including slidably connected rod sections, means for slidably supporting the rod for bodily longitudinal movement, yieldable means between one of the sections and the first means for resisting longitudinal movement of the rod as well as sliding movement of one section 105 relative to the other common to both movements, and means for adjustably varying the effective length of the rod.

3. A switch throw rod including slidably connected rod sections, means for slidably supporting the rod for bodily longitudinal movement, yieldable means between one of the sections and the first means for resisting longitudinal movement of the rod as well as sliding movement of one section 115 relative to the other common to both movements, and means connecting the rod sections and adjustable for varying the effective length of the rod.

4. A switch throw rod including telescopic rod sections, means for slidably supporting the rod for bodily longitudinal movement, and yieldable means mounted within one of the sections coacting with the first means for resisting longitudinal movement of the rod as well as telescopic move- 125 130

ment of the sections common to both movements.

5. A switch throw rod including telescopic rod sections, a plunger slidable within 5 one of the sections for supporting the rod for bodily longitudinal movement and disposed to coact with another section of the rod, and yieldable means coacting between the first section and the plunger for resisting longitudinal movement of the rod as well as telescopic movement of the sections.

6. A switch throw rod including telescopic sections, a plunger slidable within one 15 of the sections for supporting the rod for bodily longitudinal movement and disposed to coact with another section of the rod, registering slots in the plunger and said first mentioned section adapted to receive the crank pin of a switch throw lever there- 20 through connecting the rod with said lever, and yieldable means coacting between the first section and the plunger for resisting longitudinal movement of the rod as well as telescopic movement of the sections.

25 7. A switch throw rod including telescopic rod sections, a nut carried by one section housed within the other section adjustably connecting the sections, a plunger slidable within said second mentioned sec- 30 tion for supporting the rod for bodily lon-

gitudinal movement and disposed to coact with said nut, and yieldable means coacting between the latter section and the plunger for resisting longitudinal movement of the rod as well as telescopic movement of the sections.

8. A switch throw rod including slidably connected rod sections, means for slidably supporting the rod for bodily longitudinal movement, a plug closing one of the sections, and yieldable means coacting between the first means and said plug for resisting longitudinal movement of the rod as well as movement of one section relative to the other. .

45 9. A switch throw rod including slidably connected rod sections, means for slidably supporting the rod for bodily longitudinal movement, one of the sections being provided with lugs, a plug closing said section 50 notched to receive said lugs therethrough and further provided with ribs to coact with the lugs normally locking the plug against rotation, and yieldable means coacting between the first means and said plug for re- 55 sisting longitudinal movement of the rod as well as sliding movement of one section relative to the other.

In testimony whereof I affix my signature.

CHARLES H. PARTINGTON. [L.S.]
